TOE POST FOR SKI BINDING

Mitchell H. Cubberley, Nutley, N.J., assignor to
Cubco, Inc., Nutley, N.J.

Filed Mar. 5, 1973, Ser. No. 338,017

Term of patent 14 years

Int. Cl. D21—02

U.S. Cl. D34—14 D

FIG. 1

FIG. 3

FIG. 2

FIG. 4

FIG. 5

FIG. 6

FIG. 1 is a left-side elevational view of a toe post for a ski binding, showing my new design;

FIG. 2 is a front elevational view thereof;

FIG. 3 is a rear elevational view thereof;

FIG. 4 is a top plan view thereof;

FIG. 5 is a bottom plan view thereof; and

FIG. 6 is a front perspective view thereof, shown on a reduced scale.

I claim:

The ornamental design for a toe post for ski binding, as shown and described.
